BY Ralph Koenig
ATTORNEY

UNITED STATES PATENT OFFICE.

WILLIAM E. PATCH, OF ST. LOUIS, MISSOURI.

OVEN.

Application filed June 2, 1924. Serial No. 717,296.

To all whom it may concern:

Be it known that I, WILLIAM E. PATCH, a citizen of the United States, residing in the city of St. Louis, State of Missouri, have **5** invented a certain new and useful Improvement in Ovens, of which the following is a specification, reference being had to the accompanying drawings, forming a part thereof.

10 This invention relates to a certain new and useful improvement in heating ovens.

In United States Letters Patent No. 1,416,-
15 865, granted to me under date of May 23, 1922, I disclose a method or process for effecting under the action of heat in a closed oven the de-enameling of metal articles, and my present invention has for its chief object the provision of an efficient oven especially adapted, in furtherance of such **20** process or method, for the heat treatment of enameled ware and articles for effecting or accomplishing the de-enameling thereof.

With the above and other objects in view, my present invention resides in the novel **25** features of form, construction, arrangement, and combination of parts hereinafter described and pointed out in the claims.

In the accompanying drawings,—

30 Figure 1 is a perspective view of a heat-treating oven embodying my invention;

Figure 2 is a vertical sectional view of the oven on approximately the line and looking in the direction of the arrows 2—2, Figure 1;

35 Figure 3 is a broken plan view, partly in section, of the oven;

Figure 4 is a fragmental rear elevational view of the oven;

40 Figure 5 is an enlarged vertical sectional view of the oven on approximately the line and looking in the direction of the arrows 5—5, Figure 1;

Figure 6 is an enlarged fragmental sectional view of the oven; and

45 Figure 7 is an enlarged sectional view of one of the gas-supply controlling or regulating valves of the oven.

Referring now more in detail and by reference characters to the drawings, which **50** illustrate a preferred embodiment of my invention, the oven A is preferably in the form of a generally sheet metal rectilinear shell or structure suitably supported on legs 1 and comprising a bottom wall 2, opposite side walls 3—3, a top wall 4, and a rear wall 5, all suitably rigidly joined together and

each being of hollow or chambered formation for housing suitable heat-retaining insulation 6. Formed in the top wall 4, is preferably a valve or damper controlled air **60** and vapor vent 7.

Hinged to the top wall 4 at its forward margin, as at 8, for swingably closing the front end of the oven, is a door 9 adapted when closed to normally flatwise abut at its margin in heat-retaining relation against the front ends of the top, side, and bottom walls of the oven. Frequently under the intense heat of the oven or from other causes, the **70** normal tight closing relation between the door 9 and the several walls of the oven proper is affected, in which event separate angle-members 10, 11—11, and 12 disposed at and having slot and pin and nut connection at one leg as at 13, with the front end **75** portions of the top, side, and bottom walls, respectively, of the oven, are independently adjusted to provide at their other leg a flat surface for engagement with the marginal portion of the door 9 to effect a heat retaining joint between the oven and the door when the door is closed. And provided upon the inner face of the door 9 to fit when the door is closed within the frame or enclosure formed by the several angles 10, 11, and 12, is a hollow compartment or chamber 14 also containing suitable insulation **80** 6 for increasing heat retention by the door 9 when closed.

Suitably supported transversely upon the **90** rear wall 5 of the oven, is an aligning pair of fixed cross-pipes 15—15 having communicating connection by means of a T-coupling or the like 16 with a stand-pipe 17 leading from a suitable source of gas or other fuel **95** supply (not shown); and disposed along the pipes 15 in suitably spaced relation and presented towards the oven, are outlet pipe-sections 18, the bores of which are each partly reduced, as at 19, forming substantially **100** closing valve-seats for needle-valve members 20 seated for individual manipulation in the respective pipe-sections 18 for selectively controlling and regulating the flow of gas from the pipes 15 to the several sections 18. **105**

Disposed longitudinally in spaced relation within the oven and upon its lower or bottom wall 2, are burner-pipes 21 capped or otherwise preferably permanently closed at their forward end, as at 22, and each formed **110** within the oven with a longitudinal series of upwardly presented jet-orifices 23. The

several pipes 21 align with the several respective pipe-sections 18 and at their rear ends project exteriorly of the oven for supporting mixing-chambers 24, which latter at 5 their end-walls 25 have threaded engagement with the respective pipe-sections 18, as best seen in Figure 7. The end walls 25 of the several mixing-chambers 24 are formed with suitable cut-outs to provide air-entrance openings or inlets 26, and disposed for threaded movement upon the several respective pipe-sections 18 for adjustably opening and closing the apertures 26, are disk-valves 27. I might here state that, 10 while not specifically shown, the openings in the oven end-wall 5 for the several burner-pipes 21 are by means of gaskets or the like made gas-tight.

Disposed lengthwise and preferably 20 loosely for removal and replacement within the oven, is a series of suitably elongated substantially inverted channel-shaped plates or so-called burner-boxes 28 that rest at their flanges or side walls upon the bottom 25 wall 2 of the oven and bridge the several burner-pipes 21, as best seen in Figure 2, each plate or box 28 being preferably strengthened intermediate its side flanges by a supporting longitudinal wall 29 that divides its channel into substantially a pair of burner-pipe compartments.

In use and operation, the several plates 28 perform the function, as it may be said, of a false removable oven bottom, are heated 35 directly without loss of heat by the burning or ignited gas flowing from the jet-orifices 23 of the several pipes 21, and are thus adapted to support the work within the oven substantially directly over, yet without 40 impingement thereupon by, the gas-flames. The oven proper is also substantially gas or vapor tight and through its novel construction effects maximum retention of the heat of the burning gas, with the result that the 45 work is subjected to a relatively high heat and the carrying out or practicing of my mentioned de-enameling process most efficiently accomplished.

I am aware that changes in the form, construction, arrangement, and combination of 50 the several parts of my new oven may be made and substituted for those herein shown

and described without departing from the nature and principle of my invention.

Having thus described my invention, 55 what I claim and desire to secure by Letters Patent is:

1. A heat-treating oven comprising a shell, a series of perforated burner pipes disposed longitudinally in spaced relation 60 within the chamber and upon the bottom wall of the shell, and a series of work-supporting plates disposed within the shell over the several pipes.

2. A heat-treating oven comprising a 65 shell, a series of inverted work-supporting channel-shaped plates disposed within the shell and resting at their flanges upon the bottom wall thereof, and a series of burner pipes disposed upon the bottom wall of the 70 shell and within the channels of the plates.

3. A heat-treating oven comprising a shell, a series of inverted work-supporting channel-shaped plates disposed within the shell and resting at their flanges upon the 75 bottom wall thereof, a series of burner pipes disposed upon the bottom wall of the shell and within the channels of the plates, and means for individually controlling the flow of combustible fluid into the several pipes. 80

4. A heat-treating oven comprising connected top, bottom, and side walls, a door hinged to the oven for closing an end thereof, and angle-members disposed upon said walls for forming a heat-retaining joint 85 with the door when the door is closed.

5. A heat-treating oven comprising connected top, bottom, and side walls, a door hinged to the oven for closing an end thereof, and angle-members adjustably disposed 90 upon said walls for forming a heat-retaining joint with the door when the door is closed.

6. A heat-treating oven comprising a 95 shell, a plurality of separate inverted work-supporting channel-shaped plates disposed in a longitudinal series within the shell and removably resting upon the bottom wall thereof, and a series of burner pipes disposed upon the bottom wall of the shell and 100 within the channels of the plates.

In testimony whereof, I have signed my name to this specification.

WILLIAM E. PATCH.
